UNITED STATES PATENT OFFICE.

DANIEL UNRUH, OF KANSAS CITY, MISSOURI.

BOTTLE.

1,295,240.

Specification of Letters Patent. Patented Feb. 25, 1919.

Application filed December 22, 1916. Serial No. 138,437.

To all whom it may concern:

Be it known that I, DANIEL UNRUH, a citizen of the United States, residing at Kansas City, in the county of Jackson and 5 State of Missouri, have invented certain new and useful Improvements in Bottles, of which the following is a specification.

This invention relates to bottles, and more particularly to a bottle for containing poison 10 provided with means for preventing easy opening of the same.

One of the main objects of the invention is to provide a bottle of the character stated 15 of simple construction and operation having a removable cap which carries a cork or closure member and forces this member tightly into the bottle neck when secured in operative position. A further object is to provide a bottle with a cap adapted to coöperate 20 therewith so as to effectually prevent the contents of the bottle from flowing or dripping down the outside of the bottle neck. Further objects will appear from the detailed description.

25 In the drawings:

Figure 1 is a side view of a bottle constructed in accordance with my invention,

Fig. 2 is a central vertical section through the same,

30 Fig. 3 is a section on line 3—3 of Fig. 1,

Fig. 4 is an underneath view of the cap, and

Fig. 5 is a top plan view of the cap.

The bottle 1 is provided with a neck 2 35 having an integral annular shoulder at its upper end. This shoulder is divided into two outwardly extending annular shoulders 3 by two vertical diametrically opposite slots 4 extending through the same at the sides of 40 the neck 2. Each of the shoulders 3 has its lower edge portion of helical curvature to form, in effect, a screw thread 3^a. Each of these thread members is beveled inwardly and downwardly, as shown in Figs. 1 and 2 of 45 the drawings.

A cylindrical cap 5 fits on top of the neck 2 and extends outward radially of the same. This cap is provided with diametrically opposite downwardly extending arms 6 each of 50 which is turned inward at its lower end, as at 6^a, to fit snugly under the threads 3^a of the shoulders 3. This cap is provided with a central inverted frusto-conical recess which receives the upper end portion of a cork 55 stopper 7 which is adapted to fit snugly in

the bottle neck 2 so as to effect a liquid tight closure therewith. The cap 5 is placed on top of the neck 2, the stopper 7 being inserted into the neck, and the arms 6 into the vertical grooves 4. By turning the cap 60 5 toward the right, as considered in Fig. 1 of the drawings, the lower inclined portions 6^a of the arms 6 will engage the beveled lower edges 3^a of the shoulders 3 so as to draw the cap 5 firmly downward on to the 65 neck. This forces the stopper 5 tightly into the bottle neck and also brings the under face of the cap into close engagement with the upper edge of the neck 2 so as to effect a liquid tight closure therewith. For this 70 purpose a portion of the under face of the cap concentric with the central recess which holds the stopper 7 may be ground, the upper edge of the neck 2 being also ground. Also, the beveled portion or thread 3^a of the 75 shoulder 3, and the inner faces of the lower portions 6^a of the arms 6, may be ground so as to insure close frictional engagement between these members. By this means the cap 5 and stopper 7 are both secured firmly in 80 position, and a double closure is formed at the neck of the bottle which effectually eliminates all possibility of spilling of the contents of the bottle or of the poison flowing downward about the outer surface of the 85 bottle neck. The cork or stopper 7 may be readily removed from the cap 5 so as to permit renewal thereof as occasion requires, thus permitting the cap to be used a number of times, the cap and cork coöperating to 90 provide a composite closure member which operates in the manner above stated to form a double fluid pipe closure about the upper end of the neck of the container.

A disk 8 is secured on the top of cap 5. 95 This disk is provided with a suitable inscription or design such as that shown in Fig. 5 of the drawings. A person, in endeavoring to open the bottle would grasp the cap 5 so that their attention would be called to the 100 fact, in their endeavors to open the bottle in the ordinary manner, that the bottle was of unusual construction.

What I claim is:

In combination with a necked receptacle 105 having an outer enlargement at its upper end in which is formed longitudinal slots, the lower edge of the enlargement having the portions between the longitudinal slots inclined and beveled to form shoulders, a cap 110

having arms to embrace the enlargement of the neck, and having the ends of the arms bent in at an obtuse angle to pass through the longitudinal slots and engage under the 5 beveled shoulders, and a stopper carried by the cap and adapted to enter the neck and seal the receptacle.

In testimony whereof I affix my signature in presence of two witnesses.

DANIEL UNRUH.

Witnesses:

FLORENCE R. FITCH,
JOSEPHINE E. MORANHA.
